UNITED STATES PATENT OFFICE

2,381,304

LIQUID DISPENSING APPARATUS

Joseph A. Merrill, Winnetka, Ill., assignor to S. F. Bowser & Company, Incorporated, Fort Wayne, Ind., a corporation of Indiana

Application August 19, 1943, Serial No. 499,289

6 Claims. (Cl. 123—121)

The invention relates to a pressure means for dispensing gasoline from tank trucks. More specifically it relates to an expandable bag placed in a compartment of the delivery truck, into which bag gaseous butane or propane is passed under pressure to empty the compartment of liquid. The gas is then used as a fuel to operate the truck motor.

In present practice, the liquid is discharged from fuel delivery trucks by gravitational force alone and it is difficult to attain the desired unloading speeds with present gravity apparatus especially since part of the gravity head is used in passing the liquid through a meter.

It is an object of the invention to provide pressure means for dispensing liquids from tank trucks.

It is a second object of the invention to provide an expandable bag for applying pressure to the liquid in a tank truck compartment for dispensing liquid therefrom.

Another object of the invention is to provide a compressed liquid tank from which gas can be controllably released to expand an expandable bag for displacing liquid from tank truck compartments.

A further object of the invention is to provide an expandable and contractible bag from which gaseous fuel can be taken to supply engine power to the truck.

Yet a further object of the invention is to provide a selector switch which will allow the truck engine to be supplied with either a mixture of air and the gaseous fuel or ordinary carbureted gasoline.

It is still a further object of the invention to provide gaseous pressure means for dispensing liquid from tank trucks, and then making practical use of the gas to propel the trucks.

These and other objects of the invention will become apparent upon consideration of the accompanying drawing in which;

The figure is a diagrammatic view taken partially in section, of the tank compartment and bag, gas supply system, and fuel feed systems. The numeral 1 represents a pressure cylinder containing liquid propane, butane or a liquified gas of a similar nature or mixtures of such gases. In the claims, the term, "combustible fuel," shall be used to designate these gases. A manually operated valve 3 can be opened to allow gas to flow from the cylinder 1 through a pipe 5 and a pressure reducing valve 7.

The gas, having been cooled by an expansion is passed through a heat-exchanger which is

designated generally by the numeral 9. Hot water from the engine water jacket (not shown) is passed through a pump 11 and a valve to the heat exchanger tank 10. This valve 13 is controlled by a solenoid 15 which is attached to a thermostat 17 placed in the heat-exchanger tank 10 and is powered by the battery 12. Thus the water temperature in the heat exchanger 9 is controlled, the gas is uniformly heated and further expanded as it passes through the coil 14.

The heated gas then passes through a line 18 in which is inserted a three way valve 19, a pressure relief valve 21, and into the tank compartment 27 which may be selected by means of selector valve 23. An expandible bag 25, preferably of synthetic rubber, is disposed in the compartment and is connected to valve 23 by pipe 16. The resilience of the bag tends to oppose expansion, thereby providing pressure means for emitting the fluid contained when the bag is in an expanded state and it is desired to use the fluid as a fuel. The weight of the bag itself provides additional means for the pressure emission of the fluid contained. A discharge opening 28 is formed in the bottom of the compartment. This is connected by a pipe 20 to an air eliminator 22, a meter 29, a manually operated discharge valve 31 and the delivery hose 24. The synthetic rubber bag 25, is cemented to the bottom of the compartment 27 except in the region of the discharge opening 28. The discharge opening 28 is protected from being clogged with the bag 25 by a baffle plate 33. Each compartment 27, is provided at the top with a fill opening 35 and an air inlet check valve 37.

The 3 way valve 19 is connected by a pipe 26 to a Venturi gas-air mixer 39 and to the intake manifold 41 of the engine through a butterfly valve 47. A normally closed valve 58 which opens to the atmosphere, is placed in the pipe 26 near the Venturi mixer 39 which serves to mix gas and air in such proportions as to produce explosive charges for an internal combustion engine.

A selector switch 43 connects a battery 44 through contact 46 with a solenoid 45. A second solenoid 48, which is opposed to solenoid 45 is connected through switch 43 and contact 50 to the battery 44. The armature 52 is connected to operate valve 47 and a second butterfly valve 54. Both valves are operated simultaneously so as to open either the gas passage or the regular gasoline entrance to the manifold 41 and to close the other.

The regular gasoline tank 49, is connected by

a pipe 56 to the valve 54 through the fuel pump 51 and the carburetor 53.

Operation

In operation, the solenoid 48 is energized to open valve 54 and to close valve 47. The truck proceeds to its destination powered by the gasoline supplied from tank 49 by pump 51 and carburetor 53. Upon arrival the valve 3 on the cylinder is opened and the pressure reducing valve 7 delivers gas at approximately 4 p. s. i. gage to the compartment 27 selected by valve 23. The discharge valve 31 is opened and the liquid is metered from the compartment. When the compartment is emptied, the selector switch 43 is then adjusted to engage contact 46. This energizes solenoid 45, opens valve 47 and closes valve 54, and the three-way valves 19 and 58 are then changed to permit flow from the bag 25 into the manifold 41. The truck may then be driven, powered by the gas, to its next stopping point. When it is desired to again load the compartments with gasoline, any excess gas may be passed to a safe place of disposal through valve 58 or the engine may be left running until the gas is exhausted.

The liquid dispensing may be accomplished through the use of gases other than those of the combustible type as herein described. If CO₂, N₂ or other inert and non-combustible gases are used, the apparatus beyond the three-way valve 19 (the Venturi-mixer etc.) which permits power utilization of the combustible gases would be discarded. Then three-way valve 19 would be employed to allow flow to either the gas bag 25, or through pipe 26 to the atmosphere.

It is obvious that various changes may be made in the form, structure and arrangement of parts without departing from the spirit of the invention. Accordingly, applicant does not desire to be limited to the specific embodiment disclosed herein primarily for purposes of illustration; but instead, he desires protection falling fairly within the scope of the appended claims.

What applicant claims to be new and desires to protect by Letters Patent of the United States is:

1. In a liquid dispensing apparatus, a cylinder containing combustible fuel, a liquid compartment, an expansible resilient bag in said compartment adapted to receive vaporized combustible fuel from said cylinder providing means for effecting pressure delivery of liquid from said compartment, a device adapted to utilize said combustible fuel, and means for connecting said device at will to said bag.

2. In a device of the character described, a cylinder containing combustible fuel under pressure, means for vaporizing said fuel, a resilient bag adapted to receive vaporized fuel under pressure, from said cylinder, an internal combustion engine, means for conducting vaporized fuel from

said bag to said engine, and means for connecting said bag with either said cylinder or with said conducting means.

3. In a device of the character described, a cylinder containing combustible fuel under pressure, means for vaporizing said fuel, a resilient bag adapted to receive vaporized fuel under pressure, from said cylinder, an internal combustion engine, means for conducting vaporized fuel from said bag to said engine, and means for connecting said bag with either said cylinder or with said conducting means, a source of combustible gasoline vapor and manually selective means for connecting said engine with said conducting means or said source of gasoline vapor.

4. In a device of the character described, a cylinder containing combustible fuel under pressure, a valve providing manually controllable means for expanding and vaporizing said fuel from said cylinder, automatic means for regulating the temperature of said vaporized fuel, a liquid compartment, means for forcibly dispensing liquid from said compartment comprising a resilient bag in said compartment adapted to receive the vaporized fuel under pressure from said cylinder, said bag also providing means by its natural contraction for dispensing said vaporized fuel, an internal combustion engine, means for conducting vaporized fuel to said engine, means for selectively connecting said bag with either said cylinder or said conducting means, a source of gasoline vapor and manually selective means for connecting said engine with either said conducting means or said source of gasoline vapor.

5. In a liquid dispensing apparatus, a liquid compartment, an inwardly opening check valve, a normally closed fill opening, and a discharge opening disposed in said compartment, a source of fluid under pressure, means for forcibly dispensing liquid from said compartment comprising a resilient bag in said compartment, means connecting said bag to receive gaseous fluid under pressure from said fluid source, a device for consuming said fluid, means for connecting said bag at will to said device whereby fluid will flow to said device under pressure afforded by the resilient bag.

6. In a device of the character described, a source of combustible vaporized fuel under pressure, a compartment to be emptied, an expansible bag, formed of elastic material, in said compartment adapted to be expanded by said fuel under pressure to receive said fuel, said bag tending to return to its contracted form, said tendency providing means for dispensing said fuel from said bag upon reduction of said pressure, said bag upon expansion serving to displace the contents of said compartment, a device adapted to consume said fuel and means for connecting said bag to discharge fuel into said device.

JOSEPH A. MERRILL.
